Specification of Letters Patent.

Patented Oct. 9, 1917.

Application filed June 10, 1915. Serial No. 38,360.

To all whom it may concern:

Be it known that I, ALBERT C. DOWNING, a citizen of the United States, and resident of Milwaukee, in the county of Milwaukee, 5 and State of Wisconsin, have invented new and useful Improvements in Presses, of which the following is a description, reference being had to the accompanying drawings, which are a part of this specification.

10 My invention has relation to improvements in presses.

The primary object of the invention is to provide a simple and convenient press adapted for forcing down the overlying flaps of 15 a pasteboard box to cause said flaps to adhere to the glued surfaces of the underlying end flaps.

A further object is to provide a press in which the bed piece thereof is movable, preferably 20 on a pivot, whereby the said bed piece can be swung out of normal position to a convenient position for the insertion over the bed piece of the article to be operated upon.

25 With the above and other incidental objects in view, the invention consists of the devices and parts, or the equivalents thereof, as hereinafter more fully set forth.

In the accompanying drawing, Figure 1 30 is an elevation of the improved press, the handle of the eccentric cam being broken away, and the bed plate and its supporting post being shown in full line in their normal upright position, and by dotted lines as 35 swung outwardly on the pivotal connection;

Fig. 2 is an elevation at right angles to Fig. 1; and

Fig. 3 is an elevation, partly in section on the line 3—3 of Fig. 2, looking in the direction of the arrows.

Referring to the drawing the numeral 4 indicates a base frame, which may be of any desirable form, preferably of rectangular form, the said base having rising upwardly 45 from each corner thereof uprights 5. The upper ends of said uprights are also connected by a rectangular frame 6, and extending across and connected to the end bars of the upper frame is a cross bar 7. This 50 cross bar is provided centrally with an opening 8, the upper portion of said opening being of greater diameter than the lower portion thereof.

A tube 9 has its lower end fitting in the 55 enlarged portion of the opening 8, and rests

on the shoulder 10 formed at the junction of the enlarged and narrowed portions of said openings. The upper portion of this tube is split, as most clearly shown in Fig. 2, the split portion providing for the accommodation of an eccentric cam 11 provided with an operating handle 12, the said eccentric cam turning upon a pivot pin 13 which extends across the upper portion of the split and has its ends mounted in the members formed by the split. The cam 11 on one side of its curved edge is formed or provided with a stop shoulder 14, and on the opposite side of its curved edge is provided with another stop 15, which is preferably 70 in the form of a stiff flat bar secured to the edge of the cam.

Within the tube 9 is adapted to reciprocate a plunger 16, provided with a depending stem 17, said stem carrying at its lower 75 end a platen or follower. This platen or follower, preferably comprises two boards 18—18, which are held adjustably together by means of bolts 19—19 and wing nuts 20—20, the latter engaging the upper 80 threaded ends of the bolts, and adapted to be turned down against the upper side of the upper board. By this provision the thickness of the platen or follower can be either increased or decreased, when desired. 85 The thickness is increased by inserting sheets of cardboard 21, or other material, between the boards, and the thickness is decreased, of course, by removing one or more of the sheets. As the limit of the extent 90 of the downward throw of the follower is always the same, it of course frequently becomes necessary to increase the thickness of said follower so that it may adjust itself to different thicknesses of pasteboard flaps at 95 the end of the box to be operated upon.

Below the platen or follower is the bed piece or plate 22 of the press. It is one of the features of the invention to provide for a movable bed piece, which when moved out 100 of its normal position permits of the ready insertion thereover of the pasteboard box, and which when moved in the opposite direction to its normal position is in line to receive the downward thrust of the follower. 105 To this end, I prefer to mount the bed piece upon the upper extremity of a post or bar 23. The lower end of this post or bar extends between two angle plates 24—24, said angle plates extending transversely from 110

one of the side pieces to the other of the bottom rectangular frame 4.

The end of the bar 23 which lies between these two plates is mounted upon a pivot pin 25, the ends of said pivot pin being carried in the plates. The plates 24 are also connected by two stop pins 26—26 which serve respectively to limit the throw of the bar 23 and its bed piece both inwardly and 10 outwardly. The upper end of the post 23 may be connected to the bed piece 22 in any desirable manner.

In the drawing, I have shown two angle plates 27—27, their vertical members being 15 secured to the post by bolts, and their horizontal members engaging the under side of the bed piece, and being secured thereto by means of bolts 28—28 and wing nuts 29—29 turning on the lower threaded ends of said 20 bolts.

In addition to the stop pins 26—26, bracket arms 30—30 may be provided which are secured to and depend from the follower 18, and with which bracket arms the bed piece 25 22 of the press is adapted to contact, when said bed piece is in its normal upright position.

The pasteboard box to be operated upon is shown in dotted lines in the three figures 30 of the drawing, and is indicated by the numeral 31. It is desirable to provide means for supporting the lower end of the box, and as a convenient supporting means, I show two U-shaped brackets 32—32, which 35 are abutted against the post 23, and secured thereto by means of bolts 33—33, which connect the transverse members of the U-shaped brackets. The arms of these U-shaped brackets extend outwardly in opposite directions 40 and support the lower edge of the box.

The press is designed to be used for the purpose of pasting down the flaps at one 45 end of a pasteboard box, such, for instance, as a box having two underlying flaps and two overlying flaps. Before the box is placed in the press, a coating of paste is applied to the upper surfaces of the underlying flaps. The post 23, and the bed piece connected thereto are first swung outwardly 50 to the dotted line position shown in Fig. 1, and in which position the box is readily adjustable over the bed piece, with the end containing the flaps to be pasted resting upon said bed piece, and the lower edge of 55 the box resting upon the arms of the U-shaped supporting bracket 32. The post 23 and its bed piece are now turned inwardly to normal full line position. The next step is to swing to the right and downwardly the handle 12 of the eccentric cam 60 11. This will cause the edge of the cam to operate upon the upper end of the plunger 16, and cause said plunger to be moved downwardly to the compressing position shown in Fig. 2, or in other words, the

plunger is moved downwardly to such an extent as to cause the follower to press against the overlying flaps of the pasteboard box, and thus cause the said overlying flaps to be brought firmly and tightly against 70 the pasted surfaces of the underlying flaps. At the time the follower thus reaches its compressing position, the shoulder 14 of the eccentric cam engages against the upper end of the plunger 16. The operator's hand 75 can now be removed from the handle 12, and the follower will remain in its compressing position, owing to the cam being beyond the dead center, until the handle is again manually moved upwardly and to 80 the left. As the follower is thus releasably held locked in its compressing position, an operator may give his attention to another adjacent machine for the purpose of repeating the operation on that machine, and 85 so on throughout a line of presses. After the compression is continued for a desired length of time, the operator raises the handle, and after the handle passes the dead center the movement of the handle and the 90 cam will continue automatically, and the plunger 16 with its attached follower will also move upwardly, being caused to move upwardly by reason of the expansion of a coiled spring 33, which coiled spring is arranged within the tube 9 and surrounds the 95 stem 17, being confined between the shoulder form at the lower end of the plunger and the shoulder 10. When the handle is swung to the position illustrated in Fig. 1, further swinging thereof is prevented by reason of the stop arms 15 the lower ends of 100 which strike against the plunger.

What I claim is:

1. In a press, the combination of a bed 105 piece, a platen or follower, and means for adjusting the thickness of said follower.

2. In a press, the combination of a bed 110 piece, a platen or follower consisting of two members, adapted to receive one or more layers of filling pieces therebetween, and means for clampingly holding the two members together.

3. In a press, the combination of a frame, a platen or follower, means for moving said 115 platen or follower, a bed piece, and means permitting the movement of said bed piece inwardly and outwardly, said bed piece when moved outwardly being in position to receive thereover the article to be operated 120 upon, and when moved inwardly being in the line of movement of the follower.

4. In a press, the combination of a frame, a platen or follower, means for moving said 125 platen or follower, a bed piece, means permitting movement of said bed piece inwardly and outwardly, the said bed piece when moved outwardly being in position to receive thereover the article to be operated upon, and when moved inwardly being in 130

the line of movement of the follower, and a stop for limiting the extent of the inward movement of the bed piece.

5. In a press, the combination of a frame, a platen or follower, means for moving said platen or follower, and a pivoted post carrying at its upper end a bed piece, said bed piece when the pivoted post is swung outwardly being in position to receive thereover the article to be operated upon, and when moved inwardly being in the line of movement of the follower.

6. In a press, the combination of a frame, a platen or follower, means for moving said platen or follower, a pivoted post carrying at its upper end a bed piece, said pivoted post when swung outwardly permitting of

the adjustment of the article to be operated upon to the bed piece, and when moved inwardly being in the line of movement of the 20 follower, and stop pins between which the pivoted post is adapted to swing.

7. In a press, the combination of a frame, a platen or follower, a post carrying at its upper end a bed piece, and arms extending 25 from said post and adapted to act as supports for the lower edge of the article acted upon.

In testimony whereof, I affix my signature, in presence of two witnesses.

ALBERT C. DOWNING.
